(57) **CLAIM**

The ornamental design for an exercising apparatus, as shown and described.

DESCRIPTION

FIG. 1.1 is a first perspective view of an embodiment of our new design of an Exercising Apparatus;

FIG. 1.2 is a second perspective view of the design of FIG. 1.1;

FIG. 1.3 is a front view of the design of FIG. 1.1;

FIG. 1.4 is a back view of the design of FIG. 1.1;

FIG. 1.5 is a side view of the design of FIG. 1.1;

FIG. 1.6 is a top view of the design of FIG. 1.1; and,

FIG. 1.7 is a bottom view of the design of FIG. 1.1.

The broken lines showing bands and a platform is included for the purpose of illustrating portions of the "exercising apparatus," and forms no part of the claimed design.
